UNITED STATES PATENT OFFICE.

RICHARD MARX, OF PHILADELPHIA, PENNSYLVANIA.

LOOM.

Application filed April 16, 1925. Serial No. 23,584.

This invention relates to looms for weaving pile fabrics and more particularly to looms of the type employing pile wires arranged longitudinally of the fabric or in the direction of the warps.

The principal object of the invention is to provide improved means for forming the loops on the pile wires, whereby the loop-forming operation is a positive one precluding the possibility of missing.

The invention further contemplates the provision of novel and highly practicable loop-forming means constituting a material improvement over mechanisms previously used for this purpose.

In the attached drawings:—

Fig. 1 is a longitudinal sectional view of a loom made in accordance with my invention, only those parts of the loom being shown that are essential to a full understanding of the invention;

Fig. 2 is a sectional view showing in front elevation the frame which carries the wire supporting blades, together with the essential parts for actuating said blades;

Fig. 3 is an enlarged view illustrating the details of the yarn guides and the cooperative relation between these members and the pile wires;

Fig. 4 is a section on the line 4—4, Fig. 3;

Fig. 5 is a face view of one of the cutter guides and the end of the associated pile wire; and

Fig. 6 is a side view of the parts shown in Fig. 5.

With reference to the drawings, 1 designates the harness of a loom, 2 the lay, and 3 the pile wires which pass through the reed 4 and which have at their outer ends guides 5 for rotary cutters 6. The nature of the cutting means may vary largely and has no part in the present invention. In the present instance, the individual guides 5 are formed, as shown in Figs. 5 and 6, with a slot 7 for reception of the edges of the respective cutters, and are adapted to fit into sockets 8 in the ends of the pile wires 3. Clamps 9 are provided on the support 11 for retaining the guides in proper position relative to cutters and pile wires.

The other ends of the pile wires 3 are respectively supported at the upper ends of upright blades 12 mounted in a frame 13 intermediate the harness and the lay. As shown in Fig. 2, this frame comprises two uprights 14, 14, and two horizontal cross

bars 15 and 16. The bars 15 and 16 function to support a series of upright rods 18 corresponding in general with the reeds, the warp threads passing between and being separated by the rods which accordingly constitute vertical guides for said threads. As clearly shown in Figs. 3 and 4, each of the rods 18 has near the upper end flanges 19 and 21 extending transversely from the front and rear edges of the rod and in opposite directions, these flanges being widest in their middle sections and decreasing in width toward both top and bottom so as to merge easily into the sides of the rods.

The frame 13 also includes a cross bar 22 which constitutes both a support and a fulcrum for the blades 12. As shown in Fig. 1, the blades 12 are provided intermediate the ends with a hook formation 23 which fits over the top of the bar 22, and the latter, as shown in Fig. 2 is provided with a series of slots 17 in which the blades are seated, and these slots are so arranged that the blades occupy positions opposite the spaces between the rods 18. Also the cross bar 22 is offset transversely from that side of the frame adjacent the harness so that only the inwardly offset and comparatively thin and flexible upper ends 24 of the blades lie between the guide rods 18. As shown in Fig. 1, the upper extremities of the blades lie opposite the flanges 19 and 21, and at a point immediately below the flanges each of the blades has a forwardly projecting tongue 25 over which fits one end of a flat sleeve 26 in the other end of which fits the associated pile wire 3. The sleeve 26 is preferably soldered or otherwise attached to the tongue 25, and with the guides 5 secured to the respective pile wires, there is provided an easy method for withdrawing the pile wires in the event of repairs being required. After cutting the loops and releasing the clamps 9, it will be apparent that the wires may be withdrawn without difficulty.

Mounted for longitudinal reciprocation on the frame 13 below the cross bar 22 is a beam 27, and the lower recessed ends of the blade 12 fit down over this beam and extend into transverse slots whereby the longitudinal reciprocatory movement of the beam results in oscillation of the blades about their fulcrums on the bar 22. The beam is shown actuated in the present instance from the main shaft 28 of the loom through the medium of a gear 29 on the shaft and a gear

lever 31 mounted for horizontal oscillation about a pivot 32 on a bracket 33, the latter secured to the frame of the loom, not shown. One end of the lever 31 carries a roller engaging the cam while the other is pivotally secured at 34 to the beam 27.

In the present instance I have shown two sets of heddles 35 and 36. The heddle 35 has two eyelets, one for the pile warp 37 and the other for the three binder warps 38; while the heddle 36 has a single eyelet for a binder warp 39. Obviously the number and character of the warp threads may vary widely according to the nature and desired 15 characteristics of the fabric.

The mode of operation of this type of loom is in general well known to those acquainted with the art. The heddles 35 and 36 reciprocate oppositely to form the shed 20 for passage of the shuttle or shuttles and the lay operates in the usual fashion to beat in the wefts or filler threads deposited by the shuttle. The eyelet holding the pile warp 37 is so positioned in the heddle that on each upward stroke this warp is carried 25 above the top of the blade 12 and pile wire 3.

In the normal extreme positions of the beam 27, determined in the present instance by the cam 29, the upper ends of the blades 30 12 lie against one or other of the faces of the respective rods 18 between which the individual blades lie, and when so positioned the flange 19 or 21, as the case may be, of the rod 18 against which the blade lies 35 guides the warp 37 in its downward movement over and past the upper end of the blade, as will be readily understood by reference to Figs. 3 and 4 of the drawings. The positions of the blades accordingly determine 40 on which side of the various pile wires 3 the warp 37 is brought down, and the cam may be so formed and timed that this warp is successively brought down on opposite sides of the wires. The warps 37 being tied down by the filler threads, passed 45 over the warps and under the wires when the warps are depressed from loops over the wire, as indicated at 41 in Fig. 1, and these pass into contact with the cutters 6 which sever them at the top to form the pile.

By extending what in effect is the pile wire upwardly between the rods 18 so that they lie between the guide flanges 19 and 21, and by actuating the wires as described, it 55 is impossible for the warp 37 to pass down the wrong side of the pile wire, and the loop-forming operation is accordingly a positive one.

A considerable advantage of the construction 60 is found in the loose mounting of the blades 12 which permits them to be lifted freely from the support. This avoids much possible breakage. It will also be noted that the flexibility of the upper ends of the support blades provide for a bearing of these

parts against the warp guides without too fine adjustment of the parts.

There may be considerable modification without departure from the essential features of the invention, and I do not wish to 70 limit myself to the embodiment herein described and illustrated.

I claim:

1. In a loom, the combination with a warp-wise pile wire, of means including 75 mechanism for transversely moving said wire for vertically reciprocating a pile warp successively on opposite sides of said wire.

2. In a loom, the combination with a warp-wise pile wire, of warp guides, and 80 means cooperative with said guides and including mechanism for transversely moving said wire for vertically reciprocating a pile warp successively on opposite sides of 85 said wire.

3. In a loom, the combination with a warp-wise pile wire, of means for elevating and depressing a pile warp, means for transversely reciprocating the pile wire at least in part to positions on opposite sides of the 90 path of travel of said warp, and relatively stationary guide means for positively directing said warp to the side of said pile wire.

4. In a loom, the combination with spaced 95 rods, of means for reciprocating a pile warp between said rods, a warp-wise pile wire extending between said rods, means for transversely reciprocating that part of the wire lying between the rods from one side of the 100 intervening space to the other, and transverse projections on the rods to guide the warp past the top of the pile wire.

5. In a loom, the combination with spaced 105 rods, of means for reciprocating a pile warp between said rods, a warp-wise pile wire extending between said rods, a guide element projecting from each of the rods toward the other, a tongue on the pile wire projecting into the space between said guides, and means for transversely reciprocating the pile wire in that part lying between the rods to carry said tongue from one side of the intervening space to the other.

6. In a loom, the combination of spaced 115 vertical guide members, of means for reciprocating a pile warp between said guides, a support member oscillatory about an axis substantially parallel to the warp and having an upper thin and flexible end extending between said guides, a warp-wise pile wire attached to said upper end, and means for oscillating said support to alternately shift the upper end from one side of the intervening space between the said guides to 120 the other.

7. In a loom, the combination of spaced 125 vertical guide members, of means for reciprocating a pile warp between said guides, a support member positioned to one side of 130

said guides and having an upper thin end extending and movable laterally therebetween, and a warp-wise pile wire attached to said upper end.

5. 8. In a loom, the combination of spaced vertical guide members, of means for reciprocating a pile warp between said guides, a support member oscillatory about an axis substantially parallel to the warp and having an upper thin and flexible end extending between said guides, a warp-wise pile wire attached to said upper end, means for oscillating said support to alternately shift the upper end from one side of the intervening space between the said guides to the other, and a mount for said support members permitting free upward movement of the latter.

9. In a loom, the combination with spaced 20 guide rods, of means for reciprocating a pile wire between said rods, a pair of transversely misaligned guide elements project-

ing from opposite sides of the guide rods towards the adjacent rods respectively, a warpwise pile wire extending between the 25 rods and having a part lying between said guide elements, and means for transversely reciprocating the pile wire in that part lying between the rods.

10. In a loom, the combination with 30 spaced guide rods, of means for reciprocating a pile wire between said rods, a warpwise pile wire extending between said rods, a single guide element at the front and rear 35 of each of said guide rods transversely projecting in opposite directions towards the adjacent rods, a tongue on the pile wire projecting into the space between said guides, and means for transversely reciprocating the pile wire in that part lying between the 40 rods to carry said tongue from one side of the intervening space to the other.

RICHARD MARX.
